UNITED STATES PATENT OFFICE.

GEORGE C. THIESEN, OF JERSEY CITY, NEW JERSEY.

DESIGN FOR A SALAD-DISH.

SPECIFICATION forming part of Design No. 36,258, dated March 31, 1903.

Application filed February 20, 1903. Serial No. 144,341. Term of patent 3½ years.

To all whom it may concern:

Be it known that I, GEORGE C. THIESEN, a citizen of the United States, residing at Jersey City, Hudson county, State of New Jersey, have invented and produced a new, original, and ornamental Design for Salad-Dishes, of which the following is a specification, reference being had to the accompanying drawings, forming a part thereof.

10 Figure 1 is a side elevation of a salad-dish, showing my new design. Fig. 2 is a transverse section thereof. Fig. 3 is a plan view.

As shown in the drawings, the leading or material feature of my design consists of a 15 leafy effect and a representation of a lobster upon the outer surface of the sides of the dish. The leafy effect is produced by representation *a* of leaves, such as lettuce-leaves, which are ribbed and fluted for representing 20 the veins and to represent the wrinkles,

creases, or folds of the natural leaf, the leaves being represented to overlap. The rim *b* of the dish has the irregular wavy outline of the edges of the leaves. Formed in relief on the dish is the representation *c* of a lobster. As 25 shown, the lobster is so located that a portion thereof constitutes a portion of the rim of the dish.

Having thus described my invention, what I claim as new, and desire to secure by Letters 30 Patent, is—

The ornamental design for a salad-dish, substantially as shown and described.

In testimony whereof I have signed this specification in the presence of two subscribing 35 witnesses.

GEORGE C. THIESEN.
